UNITED STATES PATENT OFFICE.

BERNHARD Z. FRIEDMAN, OF FORT WORTH, TEXAS.

ADVERTISING DEVICE.

1,069,122.

Specification of Letters Patent.

Patented Aug. 5, 1913.

Application filed April 6, 1912. Serial No. 628,853.

To all whom it may concern:

Be it known that I, BERNHARD Z. FRIEDMAN, a citizen of the United States, residing at Fort Worth, in the county of Tarrant 5 and State of Texas, have invented certain new and useful Improvements in Advertising Devices, of which the following is a specification.

This invention relates to new and useful 10 improvements in advertising devices, and especially to that class which employs automatic means for consecutively exposing various printed advertisements to view.

An object of the invention is to provide 15 a series of hinged leaves so mounted that those exposed to view have the appearance of being part of a book.

Another object of the invention is to provide 20 automatic means for turning the leaves, one at a time, after an observer has had time to read the printed advertisements on the two leaves exposed.

A further object is to provide means 25 which will conceal the operating mechanism, and mystify the observer.

Finally the object is to provide an automatic advertising device which will be strong, durable, comparatively easy to construct, inexpensive to operate, and one in 30 which the various parts are not likely to get out of working order.

With these and various other objects in view, this invention has relation to certain 35 novel features of the construction and operation, an example of which is described in the following specification, and illustrated in the accompanying drawings, wherein:

Figure 1 is a perspective view of the device, showing the position of the operating 40 mechanism just before engaging a leaf. Fig. 2 is a detail end view of the cylinder in which the leaves are hinged. Fig. 3 is a detail side view of the same, showing only one leaf, and that in a vertical position.

Fig. 4 is a section of the frame of the leaf. Fig. 5 is a side elevation of the cylinder and operating mechanism, the leaves being 45 omitted. Fig. 6 is a sectional elevation taken on the line A—B of Fig. 5. Fig. 7

is a plan detail of the leaf-turning lever and pivoted pawl, and a leaf shown in position. The lever is shown in section on a line adjacent to the pawl. Fig. 8 is a detail of the slotted pawl employed to turn 50 the cylinder hereinafter to be described.

Referring now more particularly to the drawings, wherein like characters of reference designate like parts in all the figures, the numeral 1 indicates the side walls of the box-like structure which forms the base of 60 the device, and which incloses the operating mechanism. A top piece 2 is provided at the front, and a top piece 3 at the rear, to which pieces the operating mechanism is attached. A central rectangular aperture 65 4 is provided in the top, and over it is placed a casing, said casing being composed of four plates of glass 5, substantially bound together at their corners and edges, and a rear opaque plate 6, having the opening 7 in its lower edge. At the rear of the device a dummy 8 is mounted, and the hand 9 is adapted to protrude through the opening 7 in the plate 6.

The frames of the leaves 10 are constructed of sheet metal pieces having a channel section, as shown in Fig. 4, and each is composed of a base member 11, two side members 12 and a cap member 13, held to the side pieces by the pins 14. The frame 75 thus provided is adapted to receive a printed card, and to allow said card to be removed by providing the removable cap piece 13. The base member 11 is adapted to receive a rod 15, each end of which extends 80 through an aperture 16, said apertures being provided in the circular disks 17 and 18, mounted on the shaft 19. The rods 15 are made rigid with the members 11, and are adapted to turn in the apertures 16 in 85 the disks 17 and 18. The apertures 16 are positioned near the outer edges of the disks 17 and 18 in a concentric circle. A bumper 90 coil 20 is attached to each of the side members 12, being placed on one face of the leaf on one member, and on the other face on the other member. The disks 17 and 18 are rigidly fastened to the shaft 19 by means of the pins 21.

The shaft 19, which carries the cylinder 100 composed of the disks 17 and 18 and the rods 15, is rotatably mounted in bearings formed in the lower extremities of the brackets 22 and 23. The bracket 22 is attached to the top member 2, and the bracket 105 23 to the top member 3. The bearing formed in the lower end of the bracket 22 is threaded at one end to receive a threaded pointed screw 24. The point of the screw 24 is adapted to bear against the end of the 110

shaft 19, and said screw is held in adjustment by the jam-nut 25.

The top pieces 2 and 3 are so mounted on the side walls 1, and the brackets 22 and 23 so secured to said top pieces, as to give the shaft 19, and consequently the cylinder mounted thereon, a slight inclination toward the front. The object of inclining the cylinder is to enable an observer to read the advertisements printed on the leaves more readily.

The surface of the bracket 23, adjacent to the disk 18, is faced and has mounted thereon the following pivoted and slotted members which are employed to rotate the cylinder through a partial revolution, and to turn the successive leaves mounted thereon. A bell crank 26, pivoted on a stand 27, is adapted to oscillate through an arc of about ninety degrees. The two lugs 28 and 29 are formed on the arm 30 of the bell crank 26, and are adapted to receive a two pointed pawl 31. An aperture 32 in said pawl 31 is adapted to aline with an aperture in each of the lugs 28 and 29, and a spring cotter 33 is placed through said apertures, thus pivotally mounting the pawl 31 between said lugs. A curved finger or prong 34 is rigidly attached to the portion 35 of the pawl 31. The portion 36 of the pawl 31 is adapted to engage the bottom of a slight recess provided in the arm 30 between the lugs 28 and 29, and thus prevent a further rotation of said pawl 31 in a counter clockwise direction, as shown in Fig. 7. A handle 37 is secured to the arm 30 of the bell crank, and is adapted to engage suitable connecting means located in the hand 9 of the dummy 8. The pawl 31 and the prong 34 are employed to grasp and turn the leaves 10, said prong 34 being employed to prevent the pawl grasping more than one leaf at a time. A slotted pawl 38 is slidably mounted on the studs 39 and 40, which studs are screwed into the face of the bracket 23 of the bell crank 26, and is adapted to be operated by contacting with the arm 30. Said pawl is provided with a slot of two different widths, the portion 41 being only of sufficient width to slidably engage the stud 39, and the portion 42 being of a somewhat greater width than the diameter of the stud 40. The studs 39 and 40 are placed in the bracket 23 equidistant from the center of the shaft 19. The outer line of the slot 41 and 42 is continuous, and is an arc of a circle having a radius equal to the distance of said outer line to the center of the shaft 19. The portion 41 of the slot is of equal width throughout its length as is also the portion 42, a change in width occurring at the point 43. A tension spring 44 is adapted to attach at one end to a pin 45, carried by the pawl 38, and at the other end to a pin 46, carried by the

bracket 23. The spring 44 is arranged to always be under tension and its purpose is to return the pawl 38 to, and hold the same in the position shown in Fig. 6, after being displaced in a counter-clockwise direction by the arm 30 of the bell crank 26. The point 47, of the pawl 38, is adapted to engage the projecting ends 48 of the rods 15, and to impart a counter clockwise rotation to the disk 18, when said pawl 38 is operated by the arm 30 of the bell crank 26. A backward or clockwise rotation is prevented by a latch 49, which engages the ends 48 of the rods 15. Said latch is pivoted on a stud 50 screwed into the face of the bracket 23. The arm 51 of the bell crank 26 is pivotally attached at its outer end to the upper end of a connecting rod 52. The lower end of the connecting rod 52 is adapted to engage a crank pin 53, said crank pin being adjustably mounted in the slotted crank 54, which forms one of the spokes in a driving sheave 55. The driving sheave 55 is rotatably mounted on the lower extremity of a bracket 56, attached to the under side of the frame member 3.

In operation, the sheave 55 is rotated by a motor and a series of reducing sheaves, or other suitable means, through the use of a cord or belt, all of which are omitted in the accompanying drawings. When the sheave 55 is rotated, it transmits an oscillatory motion to the bell crank 26, through the use of the crank 54 and the connecting rod 52. Such oscillatory motion causes the pawl 31, mounted on the arm 30, to engage one of the leaves 10 shown dotted in Fig. 6, and to turn said leaf. During this operation, the arm 30 moves the pawl 38 and consequently the cylinder through such an arc that the latch 49 engages the end 48 of the next rod 15. As the arm 30 returns for another leaf, the spring 44 causes the pawl 38 to follow said arm until the end of the portion 42, of the slot in said pawl, is in contact with the stud 40, the extra width of the portion 42, allowing the point 47, of the pawl 38, to lift sufficient to pass over the end 48 of the next rod 15. The pawl is then ready to engage the end 48 of said next rod 15. The operation of the above-described mechanism is therefore to turn the leaves one at a time, and to rotate the cylinder in which they are mounted an amount equal to the distance between two successive leaves, and at the same time to operate the hand of a dummy, which appears to turn the leaves.

It is obvious that various changes may be made in the forms and proportions of the various parts of this invention without departing from the spirit thereof. The invention is therefore presented as including all such changes and modifications as come within the scope of the following claims.

What I claim is:

1. In an advertising device the combination with a supporting structure and a dummy provided with a movable hand placed at the rear of said structure, of a rotatable shaft, said shaft being slightly inclined toward the front of said structure, a cylinder, mounted on said shaft, a series of hinged leaves mounted on said cylinder, means connected with the hand of the dummy for turning the consecutive pairs of pages to view, and means for turning said revolute shaft as the leaves are turned.

2. In an advertising device, the combination with a supporting structure and a dummy placed at the rear of said structure, of a rotatable shaft, said shaft being mounted in said structure and being slightly inclined toward the front of said structure, a cylinder mounted on said shaft and consisting of two disks and a concentric row of rods mounted between said disks, a series of hinged leaves, said leaves being mounted on said rods of said cylinder in such a manner, that the leaves seen by an observer appear like part of a book, a sheave which may be rotated by any suitable source of motion power, a slot provided in one arm of said sheave, a crank pin, mounted in said slot, a bell crank, a connecting rod, connecting said bell crank with said crank pin, a pawl carried by one arm of said bell crank and adapted to engage one leaf after the other, means for turning said revolute shaft as the leaves are turned, and a projecting handle attached to one arm of said bell crank engaging the hand of the dummy.

3. In an advertising device, the combination with a supporting structure and a dummy placed at the rear of said structure, of a rotatable shaft, said shaft being mounted in said structure and being slightly inclined toward the front of said structure, a cylinder mounted on said shaft, said cylinder consisting of two disks and a concentric

row of rods, the ends of which project therefrom, a series of hinged leaves, said leaves being mounted on said rods of said cylinder in such a manner, that the leaves seen by an observer appear like part of a book, means for turning the consecutive pairs of pages to view, a slotted pawl, adapted to be operated by contacting with said bell crank, and arranged to engage the projecting ends of said rods of said cylinder, thus imparting a step by step rotation to said cylinder, a coiled spring, normally retaining said slotted pawl in inoperative position, a latch adapted to prevent a backward motion of said cylinder, and a projecting handle attached to one arm of said bell crank engaging the hand of the dummy.

4. In an advertising device the combination with a supporting structure and a dummy placed at the rear of said structure, of a rotatable shaft, said shaft being mounted in said structure and being slightly inclined toward the front, a cylinder mounted on said shaft, said cylinder consisting of two disks and a concentric row of rods, a series of hinged leaf frames, said leaf frames being mounted on said rods of said cylinder in such a manner, that the leaf frames seen by an observer appear like part of a book, bumper coils attached to said leaf frames, said bumper coils being fastened on opposed faces of said frames, means for turning the consecutive pair of frames to view, means for turning said revolute shaft as the frames are turned, and a handle attached to one of the means for turning frames, said handle engaging the hand of the dummy.

In testimony whereof I have signed my name to this specification in the presence of two subscribing witnesses.

BERNHARD Z. FRIEDMAN.
